UNITED STATES PATENT OFFICE.

WILLIAM S. TROWBRIDGE, OF CHICAGO, ILLINOIS, ASSIGNOR TO AMERICAN STEEL FOUNDRIES, OF CHICAGO, ILLINOIS, A CORPORATION OF NEW JERSEY.

DRAFT-ARM.

1,373,780.

Specification of Letters Patent.

Patented Apr. 5, 1921.

Application filed June 16, 1919. Serial No. 304,579.

To all whom it may concern:

Be it known that I, WILLIAM S. TROWBRIDGE, a citizen of the United States, residing at Chicago, in the county of Cook and State of Illinois, have invented certain new and useful Improvements in Draft-Arms, of which the following is a specification.

This invention relates to draft arms.

Generally speaking, in a given sense, draft arms are of two types, inside and outside. The inside type of draft arm has its upper offset vertical flange on the inner side of a center sill, and the outer type has its upper offset vertical flange on the outer side of a center sill. Whether or not an inside or outside arm is used depends upon the spacing of the center sills and the total width between the lower part of the arms for the draw bar pocket. Recently the draw bar pocket has been more or less standardized and the draw bar followers are now practically all $12\frac{1}{2}$ inches long. Consequently, the two draft arms are spaced so that the draft pocket formed by the two arms is $12\frac{1}{8}$ inches wide. If the two center sills are somewhat close together, the outside design of draft arm is used. If the two center sills are quite far apart, the inside type of draft arm is used. This is done largely for the purpose of locating the vertical bolts and passing same down through the sill and the upper horizontal flange of the draft arm in a manner to clear the main web member in the lower part of the draft arm which forms the outside walls of the pocket. The draw bar pocket and the pulling and buffering surfaces in each end of the pocket of course always have to be on the inside of the arms. Heretofore an outside design of draft arm could be used only as such, the inside design of draft arm being capable only for its particular location. If an attempt were made to use an outside draft arm as an inside draft arm, as designed heretofore, the draw bar pocket would be on the outer face of the arm instead of on the inner face of the arm. Thus it is apparent that if a draft arm could be used interchangeably as an inner draft arm or an outer draft arm, and still have the draw bar pocket on the inside, there would be many advantages in the construction and repair of the draft mechanism of cars.

To this end, one object of my invention is

to make it possible to interchangeably use a draft arm on either the inside or outside of a center sill and at the same time provide a draw bar pocket on the inner side of the draft arm of regulation width. 60

Another object is to provide a draft arm which may be used as an inner draft arm and an outer draft arm and adapted to meet all of the requirements under service conditions. 65

These and other objects are accomplished by means of the mechanism shown on the accompanying sheets of drawings, in which—

Figure 1 is a plan view of draft arms 70 embodying my invention;

Fig. 2 is a side elevation of the same;

Figs. 3, 4, 5, 6 and 7 are respectively sectional views taken in the planes of lines 3—3, 4—4, 5—5, 6—6 and 7—7 of Fig. 1; 75

Fig. 8 is a sectional view of a modified form of draft arm, the section corresponding to the section shown in Fig. 5;

Fig. 9 is a cross sectional view through coöperating draft arms of the outside type 80 and showing sills carried thereby;

Fig. 10 is a cross sectional view through the same draft arms, showing liners adjacent the sills for properly spacing same;

Fig. 11 is a cross sectional view through coöperating draft arms of the inside type 85 and showing sills carried thereby; and

Fig. 12 is a cross sectional view through the same draft arms, showing liners adjacent the sills for properly spacing same. 90

The various novel features of my invention will be apparent from the following description and drawings and will be particularly pointed out in the appended claims. 95

Referring to the figures of the drawings, it will be noted that I have shown two draft arms 10 spaced apart and connected at their front ends by a cross sill construction 11 and having mounted thereover center sills 12. 100 The front half of each draft arm is provided with a main web 13, which is arranged vertically. In connection with the vertical webs 13, particular attention is called to the section shown in Fig. 5, which is the portion at 105 which the draw bar pocket is formed. The draw bar pocket as mentioned hereinbefore must always be on the inside of the draft arm whether or not the draft arm is of the type which is mounted to the outer side of 110

the center sill or to the inner side of the center sill.

As shown in Figs. 5 and 9, the center sills 12 are embraced by offset vertical flanges 14, 5 said flanges being at the outer sides of said sills, the draft arm 10 accordingly being an outside type of draft arm. This offset vertical flange 14 projects upwardly from a transversely extending horizontally arranged portion 15 of the draft arm, the center sill 12 resting upon said horizontal portion 15. As it is necessary to have a flange along the lower side of the pocket on the outside of the web in order to secure the 15 proper amount of strength and at the same time provide means to which carry-irons may be bolted, I have provided an angle member 16, which, as shown in Figs. 5 and 9 to 12 inclusive, is riveted in each case to 20 the lower portion of the web 13. This angle member 16, however, originally is left off the arms and is riveted in place later, either on one side or the other, as may be necessary. In other words, the main vertical web which 25 forms the pocket is not provided at its lower edge with an angle member or flange until it is known whether or not the draft arm is to be used as an inner or outer type of draft arm. It is apparent, therefore, that if the 30 draft arm shown in Fig. 5 is to be used as an inner draft arm, that is, with the offset vertical flange 14 engaging the inner side of the center sill 12, as shown in Fig. 11, the same may be accomplished by securing the 35 angle member or flange 16 to the other side of the main vertical web 13. In accordance with the standardized dimensions of the various parts, assuming that the center sills ordinarily are five inches wide, the outside 40 type of draft arm is used if the center sills are spaced less than eight inches apart, while the inside type of draft arm is used if the center sills are spaced more than eight inches apart. 45 To provide for a standard width of pocket of 12 $\frac{1}{2}$ inches, as shown in Figs. 9 to 12 inclusive, the narrowest spacing of the sills 12 that could be used would be eight inches, but by using shims or liners 19, as shown in connection with the inside type of draft arm in 50 Fig. 12, a wider spacing of the sills 12 may be permitted. In other words, if the draft arms are used as inside draft arms, they could be used on sill spacing not less than 55 eight inches but greater than eight inches. Liners as thick as two inches could be used, which would make it possible to use inside draft arms on a spacing of sills anywhere between eight and twelve inches. If the outside type of draft arm is used, as shown in Figs. 9 and 10, with the same size of pocket being maintained, the widest spacing of sills that could be used would be nineteen inches overall; but by using shims or liners 19 of 60 the proper thickness, the outside type of

arm could be used with a spacing of sills of nineteen inches or under, say to fifteen inches, which for the usual standard sill would mean a spacing of approximately five inches in between the same. 70

If desired, instead of having the separate reinforcing flange or angle member 16 detachably connected to the main center web 13, the lower edge of the center web of each of the draft arms may be provided with an 75 integrally formed flange 17 on each side, as shown, for example, in the section appearing in Fig. 8. With such an arrangement, a portion of the flange formed at the lower edge of the web 13 could be cut or burned 80 away at the draw bar pocket after it was decided on what side the draft arm is to be mounted with respect to the center sill.

In either case, the draft arms may be made up as regular stock and may be used 85 interchangeably as an inside type of draft arm or an outside type of draft arm, while at the same time providing a draw bar pocket on the inside of the draft arm.

It is my intention to cover all modifications of the invention falling within the 90 spirit and scope of the following claims.

I claim:

1. A draft arm having a web and a sill flange, and means whereby a draw bar 95 pocket is formed on the inner side of said web whether the arm is used with said flange on the inner or outer side of a center sill.

2. A draft arm having a main vertical web and an offset vertical sill flange, and 100 means whereby a draw bar pocket is formed on the inner side of said web whether the arm is used with said flange on the inner or outer side of a center sill.

3. A draft arm having a web and a sill 105 flange, means whereby a draw bar pocket is formed on the inner side of said web whether the arm is used with said flange on the inner or outer side of a center sill, and strengthening means on the outer side of 110 said web.

4. A draft arm having a main vertical web and an offset vertical sill flange, means whereby a draw bar pocket is formed on the inner side of said web whether the arm is 115 used with said flange on the inner or outer side of a center sill, and strengthening means on the outer side of said web.

5. A draft arm having a web, and means whereby a draw bar pocket may be formed 120 on either side so that the draft arm may be used on the inner or outer side of an associated sill.

6. A draft arm having a web, and means whereby a draw bar pocket may be formed 125 on both sides so that the draft arm may be used on the inner or outer side of an associated sill.

7. A draft arm having a main vertical web, and means associated with said web 130

whereby the draft arm may be used either with a portion thereof on the inner or outer side of a center sill and at the same time provide a draw bar pocket on the inner side of said draft arm.

8. A cast metal draft arm having a main vertical web and a vertical flange for engaging the inner or outer sides of center sills, and strengthening means associated with said main vertical web for engaging one side thereof when the flange engages one side of a center sill and for engaging the opposite side of said web when said flange engages a side of an associated center sill.
9. A cast metal draft arm having a main vertical web and an offset vertical flange adapted to be secured to the inner or outer side of a center sill, and means detachably connected to one side of said web when said flange engages one side of the center sill and

for engaging the opposite side of said web when said flange engages an associated center sill.

10. Draft arms having flanged heads that may be attached to either the inner or outer side of center sills, webs depending from the heads, and means carried by the lower portions of the webs for supporting a draft rigging between the inner faces of the draft arm.

11. A cast metal draft arm having a web and vertical and horizontal flanges for engagement with either the inner or outer sides of a center sill, and means whereby a draw bar pocket is formed on the inner sides of said web irrespective of the manner of engagement of the arms with the center sills.

Signed at Chicago, Illinois, this fifth day of June, 1919.

WILLIAM S. TROWBRIDGE.
